SINGLE SOLE SHOE SEAM AND METHOD OF MAKING THE SAME

Salvatore Palmieri, Rochester, N. Y.

Application May 2, 1951, Serial No. 224,175

5 Claims. (Cl. 36—19)

1

The present invention relates to shoes and shoemaking and it has for its general object to provide a durable, comfortable shoe of good appearance and at lowered cost of manufacture due, in part, to the elimination of certain parts, materials and operations usually employed.

Another object of the invention is to provide a shoe which, while sturdy, possesses an extremely flexible sole structure due to the elimination of the usual insole and the employment of a single integral sole piece that serves the purposes of both an insole and an outsole.

A further object is to provide the foregoing and other advantages in constructing such a shoe with or without a welt, as will appear.

These and other desirable objects may be attained in the manner disclosed as an illustrative embodiment of the invention in the following description and in the accompanying drawings forming a part hereof, which drawings are largely diagrammatic, and in which:

Fig. 1 is a transverse, vertical section through the forepart of a shoe constructed in accordance with and illustrating one embodiment of the invention;

Fig. 2 is a fragmentary transverse section through the forepart of the shoe, illustrating preliminary steps in the method of construction basically common to the shoe of the form shown in Fig. 1 as well as the other forms of shoe shown in Figs. 3-6;

Fig. 3 is a similar fragmentary view of a finished shoe of somewhat different construction than that shown in Fig. 1, this form in Fig. 3 being preferred for most purposes;

Fig. 4 is a similar fragmentary view illustrating preliminary steps in the making of a welt shoe embodying the invention as illustrated in Figs. 5 and 6 constituting modifications of the structures of Figs. 1 and 3.

Fig. 5 is a similar fragmentary view of such welt shoe, stitched and cemented; and

Fig. 6 is a similar fragmentary view of a modified welt shoe, cemented.

The same reference numerals throughout the several views indicate the same parts.

Referring more particularly to the drawings, and first to Figs. 1, 2, and 3 thereof, in the practice of the method there is first prepared and cut to size, a sole piece 8, preferably of heavy sole leather. The rough or flesh side becomes the interior of the shoe and appears uppermost in the drawing. The edge of the sole piece is then split all the way around the margin thereof by a slit 10 extending inwardly a short way toward the central area which is left intact. This produces a top peripheral inner sole portion 12 on the flesh side of about shoe upper leather thickness and a relatively thick outer sole portion 14 on the bottom hair side. The usual upper 16 has its lasting allowance 18, or what here corresponds approximately to the usual lasting allowance, flared outwardly and superposed on the margin of the inner

2

sole portion 12, to which it is then stitched all around as indicated at 20 in Fig. 2 particularly. Both elements 18 and 12 are then trimmed back to the dot and dash line 22 of said figure, the trim line being very close to the line of stitching 20.

In the form of final shoe illustrated diagrammatically in Fig. 1, the seam thus formed is turned downwardly and inwardly through more than 90° and tucked under the insole portion 12 by producing a fold 24 in the latter. In so doing, the insole portion is distorted upwardly and the margin of the upper is reversed to an underlying position adjacent to the outer sole portion 14. The edge faces, after trimming, of the upper 16 and insole portion 12 indicated respectively at 26 and 28 are also reversed to face inwardly toward the central area of the sole piece. At the same time suitable shoe leather cement, indicated at 30, is applied to maintain the relative positions described and to securely and permanently bind the overlying upper and insole elements directly and indirectly to the outsole portion 14. In this embodiment it will be observed that the fold 24 is so extreme as to double the margin of the insole portion 12 upon itself, through approximately 180°.

It is usually preferred, however, not to fold the insole portion 12 quite so far or through such a great fold angle as is indicated in Fig. 1. The structure which is preferred for most purposes is indicated in Fig. 3, where a less abrupt fold 24 is employed, the seam not being carried all the way under the insole portion 12 but being turned only through about 90° so that the edge faces 26 and 28 are brought in direct abutment against the upper surface of the outsole portion 14 and are there cemented, strong and permanent cement being placed between the trimmed edges 26 and 28 on the one hand, and the underlying outside portion 14 on the other hand, as well as being placed in the locations 30 more conspicuously seen in Fig. 3. In this embodiment the joinder of the upper and the sole has a flatter appearance from the exterior.

If a welt construction is desired, the embodiment shown in Figs. 4 and 5 may be produced. Here, the previous preparation is substantially the same as that of Fig. 2, except that one margin of a leather welt strip 32 is overlaid upon the upper allowance 18 and is included in the stitching operation at 20 to secure it to the latter and to the insole portion 12. The trimming at 22 is as before, and the turning and cementing of the seam is substantially the same as in Fig. 3, except that a non-permanent "lasting cement" may be used, if desired, in place of the strong and permanent cement employed in Figs. 1 and 3. The other margin of the welt on the outside of the seam is laid down upon the projecting margin of the outsole portion 14 and is cemented thereto (whether by permanent cement or by non-permanent "lasting cement" as may be desired) and is then stitched to the projecting outsole por-

tion at 34. Its edge face 36, together with the edge faces 28 and 26 of the respective parts 12 and 16, are brought into direct abutment with the outsole portion as well seen in Fig. 5. This embodiment gives an extension sole effect with both visible and invisible switching which, plus the cement, results in an extremely rugged construction.

Or, the beaded welt construction of Fig. 6 may be produced. Here the elements and operations of Fig. 4 are provided and followed except that the welt 32 is made a little wider so that its outer margin 38, instead of lying wholly on the extension of the outsole portion 14, is wide enough to be folded and turned inwardly through about 270° to intervene between the stitched seam and said outsole portion to lie flat under the former and against the latter inwardly from its extreme edge and be secured directly thereto in and by the cementing operation. In this structure, the welt may conveniently be of textile fabric or other decorative sheet material, although leather can be used if preferred. A permanent structural cement is used, rather than a temporary lasting cement. All three edge faces 26, 28, and 36 abut directly upon and are cemented to the top surface of this welt margin 38 just as they so abut against the outsole portion in Fig. 5, and the bottom surface of the welt margin 38 is cemented to the outsole portion 14. This embodiment furnishes a beaded effect at the junction of the upper and the outsole portion.

In all embodiments, the sole of the shoe is made of a single piece of sole leather which serves as both the inner and outer soles of the ordinary shoe which, aside from the elimination of the extra element in the matter of cost of production, results in giving added walking comfort because of the flexibility of the single piece of leather.

Also, in all of the embodiments, the main stitching 20 which unites the upper to the sole structure is blind or hidden (by the cement 30 in Fig. 3, and by the manner of folding the leather in the other views) so that a very attractive appearance is produced. It is true that in the form shown in Fig. 5, the welt stitching 34 will show, but this stitching 34 is usually finer and more attractive in appearance than the stitching 20, so that the visibility of the stitching 34 does not detract from the appearance of the finished article as would the main structural stitching 20 if it were visible.

It is even possible, according to another embodiment of the present invention, to eliminate all stitching for uniting the upper to the sole. If this is desired, the thick sole 8 is prepared just as before, by slitting it at 10 to provide a thin insole flap portion 12 and a thick outsole portion 14. But before the upper is applied, the insole part 12 is trimmed back to a line some distance inwardly from the outer edge of the outsole portion 14; that is, trimmed to the line 22, or preferably even a little inwardly from this line. Then the upper is applied. The marginal edge of the upper, instead of being folded outwardly over the top surface of the insole flap 12 as in Fig. 2, is now folded inwardly around the outer edge of the flap 12 and inserted into the slit 10 between the insole flap 12 and the outsole portion 14, and is cemented by strong and permanent cement both to the lower surface of the insole portion 12 and to the top surface of the outsole portion 14.

The drawings show the parts on an enlarged

5 15 20 25 30 35 40 45 50

and somewhat exaggerated scale, for the sake of clarity. In the actual construction, the folds or humps or ridges 24 are completely flattened out by the lasting pressure, and do not interfere with foot comfort.

It is seen from the foregoing disclosure that the above mentioned objects of the invention are well fulfilled. It is to be understood that the foregoing disclosure is given by way of illustrative example only, rather than by way of limitation, and that without departing from the invention, the details may be varied within the scope of the appended claims.

What is claimed is:

1. A shoe embodying an integral sole the margin of which is split in the general plane thereof for a short distance toward the central area thus producing a top insole portion and a bottom outsole portion, and an upper having a marginal allowance overlying and secured to the insole portion, the latter being distorted into a downward and inward fold and both it and the marginal allowance of the upper being secured to the outsole portion.

2. A shoe in accordance with claim 1 in which the edge faces of both the marginal allowance of the upper and the insole portion abut the top surface of the outsole portion, the insole portion being made narrower than the outsole portion.

3. A shoe in accordance with claim 1 in which the fold of the insole portion doubles the latter upon itself and the edge faces of both the marginal allowance of the upper and the insole portion face inwardly toward the central area of the sole and opposite to the edge face of the outsole portion.

4. A shoe in accordance with claim 1 including also a welt having one marginal portion overlying the marginal allowance of the upper and secured thereto by the stitching and the other marginal portion extending outwardly and separately stitched to the outsole portion.

5. A shoe in accordance with claim 1 including also a welt having one marginal portion overlying the marginal allowance on the upper and secured thereto by the stitching and the other marginal portion folded inwardly and cemented between the outsole portion on the one hand and the insole portion and the marginal allowance on the upper on the other.
